UNITED STATES PATENT OFFICE.

LEONARD J. HOGG, OF PHILADELPHIA, PENNSYLVANIA.

FILING-RECEPTACLE.

1,347,272.

Specification of Letters Patent. Patented July 20, 1920.

Application filed January 11, 1916. Serial No. 71,429.

To all whom it may concern:

Be it known that I, LEONARD J. Hogg, a citizen of the United States, residing in Philadelphia, county of Philadelphia, and 5 State of Pennsylvania, have invented a certain new and useful Improvement in Filing- Receptacles, of which the following is a specification.

The present invention relates to holders 10 or receptacles for cards or sheets for records, indexing, correspondence or like data used in connection with filing systems and has for an object to provide a device for retaining in convenient accessible form a maximum 15 number of cards, sheets or other filing means in a minimum amount of floor space. A further object of the invention is to provide a filing device embodying a plurality of rotatable holders or receptacles mounted normally one above another in such close proximity as to conceal the contents of any of the holders but which in use may be independently shifted so that any desired holder may be brought to a position where its 20 contents are visible and not obstructed by the next or adjacent holder. A further object is to provide a means whereby the filed data in any one of the holders is accessible from more than one predetermined point, where- 25 by several persons may use the device at one and the same time.

For the purpose of illustrating my invention, I have shown in the accompanying drawings one form thereof which is at present preferred by me, although it is to be understood that the various instrumentalities of which my invention consists can be variously arranged and organized and that my invention is not limited to the precise 40 arrangement and organization of the instrumentalities as herein shown and described.

Referring to the drawings:

Figure 1, represents a side elevation of a 45 filing device embodying my invention.

Fig. 2, represents a side elevation of a portion of the device showing one section or holder in position allowing access to the cards.

Fig. 3, represents a detail in part section of the bearing and guide construction for the several holders.

Fig. 4 represents a section on line 1—1 of Fig. 1.

Fig. 5 represents another embodiment of 55 the invention, and Fig. 6 represents a side elevation of the standard of Fig. 5.

Similar numerals of reference indicate corresponding parts.

My present invention comprehends 60 broadly a construction embodying a plurality of card holders or containers arranged in substantially superposed relation each of which is independently rotatable and laterally removable with respect to the remaining 65 holders. In the preferred form 1 designates a pair of standards suitably spaced apart and to which the plates 2 are secured at suitable intervals in order to provide operating spaces to receive the card holders 3. Since 70 the several plates 2, as well as the holders 3 are of similar construction and coöperate in a like manner, the present description will be confined to one set, but all like parts will be given corresponding reference numerals. Taking therefore one of the plates 2 as an example, 4 designates the body part which has its ends connected respectively by screws 5 or like means to the standards 1 and is provided intermediate its ends with 75 a guide member 6 which extends laterally therefrom. This member 6 is preferably slotted as shown at 7 and has the walls of the slot undercut to form ways 8 in which one head 9 of the cross-head is mounted 80 for sliding movement. The cross-head in the present instance, consists of a hub 10 mounted for rotation upon the pin 11 the ends of which are fixed to the heads 9 as will be apparent. The heads 9 are each undercut or 85 slotted at two opposite sides 12 for the purpose of accurately engaging the ways 8 of the plate 2, it being of course understood that the head at one end of the cross-head engages with one plate while the other head 90 engages the opposite plate. Thus the lower head of one cross-head rides in the slot of the lower plate and has a guide bearing on the upper face of the plate while the upper head of the same cross-head has a guide 95 bearing in the ways of the plate above. Each plate therefore guides two of the head members one from the cross-head above and the other from the cross-head below though the parts are of course so supported and assembled as not to strike or interfere one with another. Preferably I employ a ball bearing 100 105 13 between the hub 10 and lower cross-

head 9 to take the downward thrust due to the weight of the parts. The hub 10 is preferably cast integral with the arms 14 forming a spider construction, which carries the 5 holders or card troughs 3, each of which is preferably of circular contour and substantially U-shaped in cross-section having inner and outer circumferential walls 15 and 16. The cards 17 are arranged, as here 10 shown, transversely between the walls 15 and 16, resting upon the bottom 18 and may be removed or replaced at will as desired. Suitable spacing elements 19 are provided for subdividing the cards into groups or 15 classes and these elements are preferably removable thus providing for adjustment of the size of the card groups. For this purpose, each of the elements 19 is provided with depending lugs 20 which are adapted 20 to seat in apertures 21 formed in the bottom of the card trough or holder. These apertures 21 may be located at regular or any suitable intervals and thereby provide a large number of places for positioning the 25 elements 19 for suitable grouping of the cards, and the size of the card groups thus varied at will to suit the convenience of the user. In the present embodiment of my invention, it will be noted that substantially 30 all the available space within the confines of the device is utilized, since the several holders or troughs are superposed in substantially abutting relation and in view of the laterally movable feature of each holder, it is unnecessary to provide a considerable 35 space between the holders in order to see the cards.

In Figs. 5 and 6, I have shown a modified construction embodying the broad conception 40 of a movable axis for the respective holders or receptacles and in which 28 designates a standard having its upper end formed as a bearing for a rotatable head 29. In the present instance the head 29 is in the 45 form of a cap seating upon a suitable ball race 30 supported by the standard 28 and having a plate 31 secured thereto which receives motion from a gear 32. In order to lock the head or cap 29 against rotation as 50 desired I preferably provide a spring pressed latch 33 in the form of a plunger which is guided in a fixed part of the standard and is adapted to engage the one of a 55 number of openings 34 which is in alignment therewith. The openings 34 are formed in the plate 31 so that when the plunger is in its normal position engaging one of said openings all rotary movement of the head is prevented. The latch 33 may be removed 60 from locking position by any suitable means but preferably I provide a connection 65 between a foot treadle 36 and the spring pressed detent 37 which is arranged to engage the aforesaid latch 33. The treadle 36 is fixed to a suitable rock shaft which carries

the lever arm 38 for controlling the actuation of a rack 39 through the connection 40. The return of the rack 39 to normal position is preferably by the spring 41 which also serves to maintain a clutch 43 in engagement. The spring 41 has therefore the double function of holding the clutch in engagement while under compression and causing the pinion 42 to rotate by its torsional action. A pinion 42 meshes with the 75 rack 39 and transmits motion to the spring pressed clutch 43 which actuates the bevel gear 44 for imparting movement to the gear 32. Suitable pulleys 45 and 46 are employed as guides for the respective connections 80 and 40, while the brackets 47 serve to support the actuating mechanism just described.

Referring to the holder or receptacle construction and the axial supports therefor, 48 designates a journal fixed to the head 29 and 85 having the rotatable hub 49 of one of the holder supports mounted thereon. A laterally disposed arm 50 is fixed to the upper end of the journal 48 and carries a like journal for the holder next above. The holders are 90 thus supported one above another with alternate journals in staggered relation, the result of which is to cause alternate card troughs to be projected laterally beyond the next adjacent troughs so that the contents 95 are visible and accessible. Each holder is consequently mounted substantially upon a rotatable crank arm whereby rotation of the head 29 causes the axis of each holder to move in a circular path while the respective 100 holders are, at the same time capable of being rotated upon their respective axes. In the operation of this form of the device, the operator depresses the treadle 36 whenever it is desired to rotate the several holders and 105 when the particular holder which is required has come into position, the foot treadle is released and consequently the spring latch 33 automatically prevents further rotation 110 of the holders, that is as a unit. The particular holder, however, which is to be used may be rotated independently of the others upon its journal, thereby permitting access 115 to the cards in any portion of its trough. It will be noted that simultaneously with the operation of the rack 39 to actuate the driving mechanism, the latch 33 is drawn so that the head 29 is released and is free to turn.

In connection with this foot operation of 120 the form of the device shown in Fig. 5, it will be understood that if desired the form of the device shown in Fig. 1 may be equipped with a foot operated means for causing any one of the holders to slide to one 125 side so that access may be had to the cards.

In using the term "cards" throughout the specification, I wish it particularly understood that I do so in a broad sense and that it implies the use of letter files, index- 130

ing means or any type of device for filing data and is not to be restricted or limited in any way to what is known technically as a card.

- 5 It will now be apparent that I have devised a novel and useful construction which embodies the features of advantage enumerated as desirable in the statement of the invention and the above description and while
- 10 I have in the present instance shown and described the preferred embodiment thereof which has been found in practice to give satisfactory and reliable results, it is to be understood that the same is susceptible of
- 15 modification in various particulars without departing from the spirit or scope of the invention or sacrificing any of its advantages.

What I claim is:

In a device of the character stated, the 20 combination of a plurality of holders for filing devices, crank arms forming respectively journals for said holders, and common means for connecting and supporting said crank arms for rotary movement, 25 whereby a plurality of said holders may be simultaneously swung to a new position and each being independently rotatable of the others.

In testimony whereof, I have hereunto 30 signed my name.

LEONARD J. HOGG.
